UNITED STATES PATENT OFFICE

VICTOR BACHAND, OF WORCESTER, MASSACHUSETTS

SHOE SKATE

Application filed March 24, 1931. Serial No. 524,996.

The present invention relates to a shoe skate and has for its prime object to provide means whereby a skate may be effectively attached to a shoe in a quick and easy manner 5 and may be easily detached therefrom and the shoe used for walking purposes to and from the pond or other skating place.

A still further important object of the invention resides in the provision of a 10 skate attaching means of this nature which is exceedingly simple in its construction, strong and durable, easy to manipulate, compact and convenient in its arrangement of parts, thoroughly efficient and reliable in use and otherwise well adapted to the purpose for which it is designed.

With the above and numerous other objects in view as will appear as the description proceeds, the invention resides in certain 20 novel features of construction and in the combination and arrangement of parts as will be hereinafter more fully described and claimed.

In the drawings:

25 Figure 1 is a side elevation of my improved skate structure attached to a shoe.

Figure 2 is a top plan view of the skate.

Figure 3 is a bottom plan view thereof.

30 Figure 4 is a bottom plan view of the shoe attachment.

Figure 5 is a sectional view taken substantially on the line 5—5 of Figure 1.

Figure 6 is a sectional view taken substantially on the line 6—6 of Figure 1.

35 Figure 7 is a sectional view taken substantially on the line 7—7 of Figure 4, and

Figure 8 is a fragmentary perspective view showing a projecting portion of the skate sole plate.

40 Referring to the drawings in detail it will be seen that the numeral 5 denotes a plate to be attached under the sole of a shoe and is formed with an enlarged opening therein and on its side has depressed therefrom pocket portions 6, the inner portions of the side walls of which are provided with notches 7. Numeral 8 denotes a heel plate adapted to be attached to the heel of a shoe and is formed with an enlarged opening and has its 45 sides provided with depressed pockets 9 op-

posite each other and its front formed with a depressed portion 10 so as to properly support the heel of the shoe in walking in conjunction with the portions 9. These plates 5 and 8, of course, are shaped to fit the respective portions of the shoes to which they are attached and may be made of sheet metal or the like having the desired resiliency or flexibility necessary for comfortable walking to and from the skating pond or other skating place.

55 The skate comprises a blade or runner 11 of any desired formation and has supported above its front portion a sole plate 12 and above its rear portion a heel plate 14. The sole plate 12 has its intermediate portion restricted in width to form a pair of projections or corners 15 to be received in pockets 6. The heel plate 7 is formed with grooves 16 in the bottom thereof disposed transversely and adapted to slidably receive portions *a* of angular shaped members 17. The other portions *b* have threaded therethrough threaded portions of a shaft 18 journaled through a portion 19 of the blade to which the blade 14 is attached.

60 It will be noted by an inspection of Figure 3 that the shaft 18 is oppositely threaded on its end portions so that when the shaft is turned by means of a key or the like engaged with the square ends 20 thereof, the members 17 will be either drawn toward each other or moved away from each other. In the forward edge of the plate 14 there is provided a notch 21 to receive the projection 10.

65 Now to put the skate on the shoe, the skate is placed thereunder and then slid rearwardly causing the projections 15 to slide through the notches 7 and to be seated in the pockets 6. Then the shaft 18 is turned to move the members 17 away from each other so that they will project into the pockets 9. Thus the skate is very securely attached to the shoe with practically the same efficiency and effectiveness as the combination shoes and skates now commonly in use.

70 It is thought that the construction, operation, utility and advantages of this invention will now be quite apparent to those skilled

in this art without a more detailed description thereof.

The present embodiments of the invention have been described in considerable detail merely for the purposes of exemplification since in actual practice it attains the features of advantage enumerated as desirable in the statement of the invention and the above description.

10 It will be apparent that changes in the details of construction, and in the combination and arrangement of parts may be resorted to without departing from the spirit or scope of the invention as hereinafter claimed or sacrificing any of its advantages.

15 Having thus described my invention, what I claim as new is:

1. In combination, a plate adapted to be attached to a shoe sole and formed with 20 pockets having notches leading thereinto, a skate having a sole plate with projections which may be slid into said pockets, a plate adapted to be attached to a shoe heel and having oppositely disposed pockets, a heel 25 plate on the skate, members slidable laterally in the skate heel plate to project into the shoe heel plates' pockets, and means for actuating said members.

2. In combination, a plate adapted to be 30 attached to a shoe sole and formed with pockets having notches leading thereinto, a skate having a sole plate with projections which may be slid into said pockets, a plate adapted to be attached to a shoe heel and having oppositely disposed pockets, a heel 35 plate on the skate, members slidable laterally in the skate heel plate to project into the shoe heel plates' pockets, a shaft journaled through the skate and having oppositely threaded portions engaged in the members.

3. In combination, a plate for attachment 40 to a shoe sole and formed with a laterally extending pocket forming part at each side thereof, a skate having a sole plate formed 45 with a folded part at its side edges, the pocket forming portion having notches in their sides through which the folded part will pass into the pocket, and means for detachably connecting the heel of the stake to the heel of 50 the shoe.

In testimony whereof I affix my signature.
VICTOR BACHAND.
